US0D1095502S

(12) **United States Design Patent** (10) **Patent No.:** **US D1,095,502 S**
(45) **Date of Patent:** **** Sep. 30, 2025**

(54) **ANTENNA**

(71) Applicant: **Avery Dennison Retail Information Services LLC**, Mentor, OH (US)

(72) Inventor: **Ian J. Forster**, Chelmsford (GB)

(73) Assignee: **Avery Dennison Retail Information Services LLC**, Mentor, OH (US)

(**) Term: **15 Years**

(21) Appl. No.: **29/929,636**

(22) Filed: **Feb. 23, 2024**

(51) LOC (15) Cl. **14-03**

(52) U.S. Cl.

USPC **D14/230**

(58) **Field of Classification Search**

USPC ..... D14/230, 231–240, 203–229, 138, 358, D14/289, 292, 300, 364–368, 188, 184; D12/42–43; D13/182, 123, 158, 162, D13/199; D24/122, 124, 199, 200, 206; D18/17, 18; D19/1; D20/22; D11/3 CPC H01Q 1/12; H01Q 1/00; H01Q 1/088; H01Q 1/10; H01Q 12/01; H01Q 9/285; H01Q 9/045; H01Q 19/30; H01Q 19/12; H01Q 1/38; H01Q 1/243; H05K 11/001; H05K 11/00; G05D 1/0234; H04B 1/0475; H04B 1/034; H03B 1/034; B05K 11/00
